UNITED STATES PATENT OFFICE.

PHILO MALTBY, OF CLEVELAND, OHIO, ASSIGNOR OF TWO-THIRDS TO FRANK D. MALTBY, OF NEW YORK, N. Y., AND L. G. HINE, OF WASHINGTON, D. C.

REVERSING-VALVE GEAR.

SPECIFICATION forming part of Letters Patent No. 333,473, dated December 29, 1885.

Application filed November 7, 1885. Serial No. 182,116. (No model.)

To all whom it may concern:

Be it known that I, PHILO MALTBY, a citizen of the United States, residing at Cleveland, in the county of Cuyahoga and State of Ohio, have invented certain new and useful Improvements in Reversing-Valve Gear for Steam-Engines; and I do hereby declare the following to be a full, clear, and exact description of the invention, such as will enable others skilled in the art to which it appertains to make and use the same.

This invention relates to that class of engines known as "marine propellers;" and the novelty consists in the construction, arrangement, and adaptation of the valve-shifting mechanism, as will be more fully hereinafter set forth, and specifically pointed out in the claims.

In this class of engines as heretofore constructed the lead of the valve or cut-off has been regulated by means of an auxiliary slide-valve arranged to work upon the main slide-valve and operated by an additional valve-rod and radius-arm and an eccentric, which further complicates the engine and is an additional item of expense. I provide for adjusting the lead of the valve while the engine is running. I operate the valves by a single eccentric mounted on the driving-shaft, in connection with suitable and inexpensive and uncomplicated mechanism, whereby the lead and throw of the valves may be regulated while the engine is in active operation, and the piston at the end of each stroke is cushioned by dead or exhaust steam.

In the accompanying drawings, which form a part of this specification, Figure 1 is a perspective view of my improved engine with my valve-shifting mechanism in operation. Fig. 2 is a vertical longitudinal section of the engine-cylinder and its chests and valves. Fig. 3 is a top plan view. Fig. 4 is an end elevation. Fig. 5 is an end elevation taken opposite to the elevation shown in Fig. 4, showing the other side of the engine. Fig. 6 is an enlarged detail. Fig. 7 is a horizontal section through the cylinder, showing the location and relation of the reversing-valve with the shifting-valves. Fig. 8 is a vertical sectional view of a detail.

Most of these views are illustrated and briefly described in an application filed by me June 9, 1885, Serial No. 168,107, for reversing-valve.

Referring to the drawings, A designates the piston, and B the main shaft, the two having the ordinary crank-connection, b. The piston works in a cylinder, C, formed in a body, C', supported by standards upon a base, which also provides journal-bearings for the main shaft. These parts, except the cylinder-body C, are of ordinary construction.

Formed in the cylinder-body are valve-chests C⁶ C', one arranged upon each side of the cylinder C, and in each of these chests operates a double-headed piston. To one of these pistons I refer by the character S, and to the other by the character S'.

In a valve-chest, D, operates a reversing-valve, E, having central exhaust-port, e, and connected vertical recesses e² and horizontal recesses e¹, as fully set forth in the application hereinbefore referred to.

Formed in the cylinder-body is a vertical steam-chamber, c, which by ports f above and f' below is connected to the valve-chest C⁶, and by a central port, c², is connected to the valve-chest D. A port, c³, connects the valve-chest D with the chest C' of the shifting valve S', and each of the valve-chests C⁶ and C' are connected above and below to the cylinder C by ports c⁴. The stem E' of the reversing and throttle valve extends up through the casing and carries a ratchet-lever, E², which, engaging a toothed segment, E³, allows the valve E to be conveniently set in either of three positions—namely, first, in the center, to shut off the live steam and stop the engine; second, to throw the live steam into the valve-chest C' through the port e², to start the engine ahead; and, third, to throw the live steam into the valve-chest C⁶ through the port e¹, to reverse the engine. The valve S operates in the chest C⁶, and the valve S' in the chest C'. Both these valves are thrown, by mechanism yet to be described, simultaneously in the same direction, but one at a greater speed than the other, as will presently appear. The ports c⁴ are differently inclined, as shown in Fig. 2, so that while their openings into the cylinder C

are upon the same approximate planes above and below, their openings within one valve-chest are much nearer together than in the other. This is made necessary in order to admit steam into the ends of the valve-chests.

I move my exhaust-valve the fastest, and instead of giving this valve a lead in order to promptly get rid of dead-steam, I am enabled to set my valves alike, and by giving a quicker motion to the exhaust-valve I provide for the proper exhaust without even enlarging the exhaust-ports.

By referring to Fig. 2 it will be seen that the several ports c^4 are closed by the heads of the piston-valves S S' , and in such position the pressure of steam within the cylinder C acts strongly to force each valve over against the side of its chest farthest from the cylinder. I balance the valves from this pressure by forming in the walls of the chests C C' , opposite each port c^4 , a blind-port, c^5 , of the same area as the port c^4 , and from each of these blind-ports c^5 is led toward the end of the chest a shallow way, c^6 ; hence when the valve head or plug covers a port c^4 the pressure from the cylinder is balanced by steam in the blind-ports c^5 , which is admitted through the way c^6 , and as the head uncovers either port c^4 it also uncovers an equal area of the blind-port c^5 . If the area of each blind-port c^5 is slightly greater than that of the port c^4 opposite, the effect will be to hold the valves to the port with a gentle influence sufficient to cause efficient working. This arrangement has peculiar advantages to the construction of valves and valve-gear shown, and it materially modifies the operation of my valve mechanism. The valve-stems s s of the valves S S' work through separate stuffing-boxes, s' , adjustably held to the cylinder-head, as shown.

Secured upon the shaft B is an eccentric, K , having a strap, I , which, by a rod, K' , is connected to a block, L , arranged to be moved in either of two directions upon a radius-arm, M , by a crank and toothed disk, R , journaled in the block L , and having its teeth r engage a series of holes or recesses, m , formed in the upper edge of said radius-arm. The arm M is rigid with a rock-shaft, N , journaled in bearings P , and this rock-shaft extends along one side of the engine and projects beyond the line of its front, where it carries rigidly a straight arm, M' , corresponding with the radius-arm M . As the shaft B revolves, the arms M and M' , through the block L and its eccentric connections, are given regular motion, with the rock-shaft N for a center.

Loosely hung on the rock-shaft N , adjacent to the radius-arm M , is a radius-arm, Q , which carries a block, Q' , the said block being connected by a pitman, T , with a sliding plate, T' , moving in guides t , formed upon the rear of the cylinder-body C' .

At the lower end of the slide T' is adjustably secured an arm, T'' , which embraces the guide at one end and is secured thereto by a set-screw, t'' , and at the other end has a hole,

t'' , through which is projected the lower end of the valve-stem s of the valve S' . The arm T'' and valve-stem are secured together by clamp-nuts u' . The free end of the adjustable radius-arm Q operates in a slot, v , formed in the plate V , carried upon the end of the radius-arm M , and a clamp or screw, v' , allows the radius-arm Q to be adjusted up or down in the plate V at will. The block Q' may be moved along on the valve-radius Q by an elbow-lever, Q'' , loosely hung on the shaft N , and having secured to its vertical arm a toothed rod, Q'' , the teeth q of which engage a horizontal pin, q' , in the block Q' , and allow the said block to be moved in either direction. This radius-arm Q , it will be understood, may be adjusted at will to vary the lead and throw of the valve S' . The valve S , which is located at the front of the engine, is adjusted by similar means. A sliding plate, U , works in guides u upon the front of the cylinder, and is connected to the stem of the valve S by a link or pitman, U' . This slide is connected to a block, U'' , adjustably hung on a radius arm, U'' . This valve-radius U'' is loosely hung on the shaft N adjacent to the rigid arm M' , and the end of the radius U'' may be similarly adjusted in the block V' by the screw v'' . Now it will be observed that greater or less throw may be given the valves by simply moving the block L upon the radius-arm M in one or the other direction. It will also be seen that the throw of the valve S' may be varied by moving the block Q' on the valve-radius Q toward or away from the pivot or shaft N , and that the throw of the valve S may be similarly varied by a similar manipulation of the block U'' on the valve-radius U'' ; but in case the range of such adjustments are not sufficient—and I find them insufficient for all the purposes of this invention—I have a still further adjustment at hand—namely, either valve-radius Q or U'' may be adjusted independently, and held at any desired point of adjustment in the plates V V' . By this latter arrangement I secure to each valve independent adjustment of the action accruing from the rock-shaft and its rigid arms M M' , and I can also at a moment's notice change the lead of either valve.

In practice, and running at a speed of, say, one hundred revolutions per minute, a proper adjustment of the exhaust will prevent pounding; but that adjustment will not prevent pounding if the speed is quickened to, say, four hundred revolutions per minute.

By my construction and arrangement I allow the engineer to adjust both the lead and the exhaust so as to use dead-steam as a cushion, and by a slight manipulation of the parts described to so regulate the exhaust as to instantly meet any emergency which may follow a change of speed. If the engine labors, he may readily increase its exhaust; if it pounds, he may quickly choke the exhaust, all being done while the engine is running.

While I describe cushioning the piston with exhaust-steam, (I prefer that method,) it will

be obvious from my construction that I may adjust so as to use live steam for this purpose, should it be desired.

What I claim as new is—

- 5 1. In a steam-engine substantially as described, the combination, with a reversing-valve, as E, and with shifting-valves operating in chests upon opposite sides of the main cylinder, of radius-arms, and adjustable connections between said arms and valves, whereby both the throw of the valves and the amount of feed and exhaust may be regulated at will, and the stroke of the piston may be cushioned with exhaust-steam, as specified.
- 15 2. The combination, with the cylinder C, chests C⁶, C⁷, and D, and the reversing and throttle valve F, of valves, as S S', radius-arms, and adjustable connection, whereby both the throw of the valves and the amount 20 of feed and exhaust may be regulated at will while the engine is running, as set forth.
- 25 3. The combination, with a cylinder and two valves, as described, of a single eccentric upon the main shaft, a radius-arm connected with said eccentric and rigidly hung upon a rock-shaft, two radius-arms, and sliding connections with said arms, whereby the throw of either valve may be independently adjusted at will, as set forth.
- 30 4. In an engine as described, the combination, with a rock-shaft operated by a single eccentric, of loose radius-arms, connections between said arms and the valves, as S S', and means, as described, for adjusting said radius-arms independently, to regulate the throw of 35 the valves at will, as set forth.
- 40 5. In an engine as described, the combination, with a rock-shaft, as N, operated by a single eccentric and carrying rigid arms M M', of loose radius-arms independently adjustable upon said rigid arms, and having adjustable connection with the valves S S', as specified.
- 45 6. The arms M M', having slotted plates V

V', and carried rigidly upon a rock-shaft operated by a single eccentric, of valve radius-arms, as Q U³, having adjustable connections with the valves, and clamps or screws v' v³, as specified.

7. In an engine substantially as described, the combination, with the piston, cylinder, valves, and valve-chests, as shown, of the arms M M', for giving to both valves simultaneous motion in the same direction, and connections for adjusting the throw of either valve at 55 will, as set forth.

8. In a steam-engine as described, a radius-arm, as M, and adjustable connections with a main eccentric, combined with a slotted plate, V, carried on said arm, a valve-radius having 60 adjustable connection with the valve, and means, as v, for changing the lead of the valve, as set forth.

9. In a reversing steam - engine substantially as described, two feed and exhaust 65 valves arranged on either side of the main cylinder, operated from a single eccentric, and set correspondingly at the commencement of each stroke, combined with connections between said shaft and valve to move the exhaust-valve at a greater rate of speed in the same direction than the feed-valve, to allow for prompt exhaust without setting the exhaust-valve at a lead, as set forth.

10. In an engine substantially as described, 75 the combination, with the cylinder and valve-chests C⁶ C⁷, arranged as shown, of the valves S S', and mechanism, as described, for adjusting the lead of either valve while the engine is running, and steam-spaces c⁵ c⁶, formed in 80 the valve-chests opposite the ports c⁴ of the cylinder, to balance the valves, as set forth.

In testimony whereof I affix my signature in presence of two witnesses.

PHILO MALTBY.
